CLAIM

The ornamental design for a shoe upper, as shown and described.

DESCRIPTION

FIG. 1 is a right side elevational view of a shoe upper showing my new design;

FIG. 2 is a top plan view thereof;

FIG. 3 is a bottom plan view thereof;

FIG. 4 is a right side elevational view thereof;

FIG. 5 is a front elevational view thereof; and

FIG. 6 is a rear elevational view thereof.

The broken line showing of a shoe side in FIG. 1 is for illustrative purposes only and forms no part of the claimed design.

Fig. 1.

Fig. 2.

Fig. 3.

*Fig. 4.**Fig. 5.**Fig. 6.*

UNITED STATES PATENT AND TRADEMARK OFFICE
CERTIFICATE OF CORRECTION

PATENT NO. : Des. 300,181

DATED : March 14, 1989

INVENTOR(S) : Suzann Jimenez

It is certified that error appears in the above-identified patent and that said Letters Patent is hereby corrected as shown below:

On the title page, in the Description, in the fifth line which reads "FIG. 4 is a right side elevational view thereof" change the line to read as --FIG. 4 is a left side elevational view thereof--.

Signed and Sealed this
Sixth Day of July, 1993

Attest:

MICHAEL K. KIRK
